(57) **ABSTRACT**

The method of the present invention generally involves a typical casino or cardroom game modified to include a progressive jackpot component. During the play of a Twenty-One game, for example, in addition to this normal wager, a player will have the option of making an additional wager that becomes part of, and makes the player eligible to win, the progressive jackpot. If the player's Twenty-One hand comprises a particular, predetermined arrangement of cards, the player will win all, or part of, the amount showing on the progressive jackpot. This progressive jackpot feature is also adaptable to any other casino or cardroom game such as Draw Poker, Stud Poker, Lo-Ball Poker or Caribbean Stud™ Poker. The apparatus used to practice the present invention comprises a gaming table, such as those used for Twenty-One or poker, modified with the addition of a coin acceptor that is electronically connected to a progressive jackpot meter. When a player drops a coin into the coin acceptor, a light is activated at the player's location indicating that he is participating in the progressive jackpot component of the game during that hand. At the same time, a signal from the coin acceptor is sent to the progressive meter to increment the amount shown on the progressive meter. At the conclusion of the play of each hand, the coin acceptor is reset for the next hand. When a player wins all or part of the progressive jackpot, the amount showing on the progressive jackpot meter is reduced by the amount won by the player. Any number of gaming tables can be connected to a single progressive jackpot meter.

BACKGROUND OF THE INVENTION

This invention relates generally to casino or cardroom gaming involving a progressive jackpot. More particularly, it relates to a progressive jackpot that is available to be played by participants in various casino or cardroom table games.

It has become common practice in gaming establishments to provide a progressive jackpot component in connection with electronic or mechanical gaming devices, such as slot machines, video poker machines or keno machines. Typically a plurality or "bank" of machines are electronically interconnected to a common progressive jackpot meter. As gaming tokens are fed into each machine, the amount shown on the jackpot meter progresses incrementally until some lucky player lines up the winning combination, such as three or four 7's on the same row of a slot machine. In video poker, a Royal Flush normally wins the jackpot, although in some variations, a player must achieve a Royal Flush in an exact order, such as A-K-Q-J-10 from left to right, or in a particular suit, such as Spades. In video keno, a player typically must match 15 out of 15 numbers to win the progressive jackpot.

It is an object of the present invention to provide a progressive jackpot component to typical casino or cardroom table games such as poker or Twenty-One.

It is a feature of the present invention to have each participant in the progressive jackpot component win all or part of the amount shown on the progressive jackpot meter if the participant achieves a particular predetermined playing hand.

It is an advantage of the present invention that when the progressive jackpot component is added to typical table games such as poker or Twenty-One that the players will enjoy these games more and that the amount of play will increase.

It is a further object of the present invention to provide apparatus useful in providing the progressive jackpot component to casino or cardroom table games such as poker or Twenty-One.

It is a further feature of the present invention to have a progressive jackpot meter electronically interconnected to one or more gaming tables to allow each player at his playing location to participate in the progressive jackpot component by wagering a gaming token which automatically activates an indicator showing the player's participation and also automatically increments the progressive jackpot meter.

It is an advantage of the present invention that the apparatus makes it easy for each player to participate in the progressive jackpot component of the game.

BRIEF SUMMARY OF THE INVENTION

The method of the present invention generally involves a typical casino or cardroom game modified to include a progressive jackpot component. During the play of a Twenty-One game, for example, in addition to this normal wager, a player will have the option of making an additional wager that becomes part of, and makes the player eligible to win, the progressive jackpot. If the player's Twenty-One hand comprises a particular, predetermined arrangement of cards, the player will win all, or part of, the amount showing on the progressive jackpot. This progressive jackpot feature is also adaptable to any other casino or cardroom game such as Draw Poker, Stud Poker, Lo-Ball Poker or Caribbean Stud™ Poker.

The apparatus used to practice the present invention comprises a gaming table, such as those used for Twenty-One or poker, modified with the addition of a coin acceptor that is electronically connected to a progressive jackpot meter. When a player drops a coin into the coin acceptor, a light is activated at the player's location indicating that he is participating in the progressive jackpot component of the game during that hand. At the same time, a signal from the coin acceptor is sent to the progressive meter to increment the amount shown on the progressive meter. At the conclusion of the play of each hand, the coin acceptor is reset for the next hand. When a player wins all or part of the progressive jackpot, the amount showing on the progressive jackpot meter is reduced by the amount won by the player. Any number of gaming tables can be connected to a single progressive jackpot meter.

BRIEF DESCRIPTION OF THE DRAWING

FIG. 1 is shows the apparatus of the present invention using a casino gaming table with coin acceptors at each playing location electronically connected to a progressive jackpot meter.

FIG. 2 shows an alternate embodiment of the present invention using a cardroom gaming table with coin acceptors at each playing location electronically connected to a progressive jackpot meter.

FIG. 3 shows a block diagram of the operation of the present invention.

FIG. 4 shows a schematic diagram of the electronic circuitry of the present invention.

FIG. 5 shows a block diagram of a plurality of gaming tables connected to a single progressive jackpot meter.

DETAILED DESCRIPTION OF THE PREFERRED EMBODIMENT

As shown in FIG. 1, a casino gaming table 10 is provided having a plurality of playing locations 12 for players participating in the game being conducted, e.g., Twenty-One. A dealer is positioned at the dealer's location 14 adjacent a chip rack 16. Adjacent to each player location 12 is a coin acceptor 20. Each coin acceptor 20 is electronically connected to a main control board 40 to which is connected a number of odometer-type counters 42 corresponding to the number of playing locations 12 provided on the gaming table 10. As shown in FIG. 1, seven playing locations 12 are preferably provided, although the number of playing locations can be more or less than seven. A reset switch 50 is

located adjacent the dealer's location **14** and is electronically connected to the main control board **40** and provides a means whereby the dealer can reset the coin acceptors **20** prior to the beginning of the play of each hand. A lockout switch **55**, is also provided adjacent to the dealer's location **14** which is activated by the dealer to prevent later wagering as will be more fully explained herein.

A main control board **40** is electronically connected to a progressive jackpot control box **60** which receives the signals from each coin acceptor **20** and in response to those signals increments the progressive jackpot meter **70**, as will be more fully explained herein. Also electronically connected to the progressive control box **60** is the jackpot reset control **80** which provides means for resetting the amount shown on the progressive jackpot meter whenever a player wins all, or part of, the amount shown on the progressive jackpot meter **70**.

In operation, the present invention operates as follows. A conventional Twenty-One game is conducted on gaming table **10**. At the beginning of each hand, each player, in addition to making his usual wager for the play of the Twenty-One hand, may also make an additional wager to be eligible to participate in the progressive jackpot component of the game during that hand. To do so, a player places a gaming token into the coin acceptor **20** associated with that player's particular playing location **12**. As will be more fully explained herein, the coin acceptor **20** "recognizes" that a gaming token has been placed therein and an indicator signal **22**, preferably a light, adjacent to the coin acceptor **20** is activated showing that that particular player is participating in the progressive jackpot component of the game during the play of that hand.

Besides activating the indicator signal **22**, the coin acceptor **20** also sends an electronic signal to the main control board **40**. This signal is sent by the main control board **40** to the odometer-type counter **42** corresponding to the particular playing location **12** to keep a sequential count of the number of gaming tokens that are placed in the particular coin acceptor **20**.

The main control board **40** also activates the progressive jackpot control box **60** which in turn controls the progressive jackpot meter **70**. Each gaming token placed in a coin acceptor **20** results in the amount shown on the progressive jackpot meter being increased by a predetermined amount. If, for example, each gaming token has value of one dollar, then the amount shown on the progressive jackpot meter would be increased by any amount up to one dollar for each gaming token placed into a coin acceptor **20**. In the preferred embodiment of the present invention, the progressive jackpot would be increased between 93% and 97% of the amount of each gaming token being wagered, the balance representing the house's share of the amount wagered for providing the progressive jackpot component of the game.

When each player has had a reasonable opportunity to make a progressive jackpot wager, the dealer activates lockout switch **55** which deactivates each coin acceptor **20**. Any tokens placed in a coin acceptor **20** after lockout switch **55** is activated will not register. This prevents late wagering after the cards are dealt.

The amount shown on the progressive jackpot meter will continue to increase for each gaming token wagered until a player achieves a winning hand. Preselected winning hands earn a player all or part of the amount shown on the progressive jackpot meter. In a preferred embodiment, the preselected winning hands and payoff amounts in Twenty-One game are as follows:

Winning Hand	Amount of Jackpot
Four 5's and an Ace	100%
Ace, two, three, four, five and six	4%
Six, seven and eight of same suit	100 tokens
Three 7's	50 tokens

The invention is not limited to these particular combinations of winning hands or payoffs; other winning hand combinations or payoff amounts can be utilized.

When a player achieves a winning hand, the jackpot reset control **80** is manually activated by pushing a button that corresponds to the type of hand that the player achieved. The amount won by the player is thus electronically deducted from the amount showing on the progressive jackpot meter.

When a particular hand is completed at gaming table **10**, the dealer presses the reset switch **50**, which deactivates the indicator signal **22**. Lockout switch **55** is also manually deactivated by the dealer. The coin acceptor **20** is thus readied to receive another gaming token for the next hand.

The progressive jackpot component of the present invention can also be used in connection with other types of casino games, e.g., Caribbean Stud™ Poker, which is the subject matter of U.S. patent application Ser. No. 102,374 filed Apr. 18, 1988, which is incorporated herein by reference thereto. Caribbean Stud™ Poker is a modification of conventional five-card stud poker. Each player makes an ante and a dealer deals five cards to each player and to himself. The player's cards are dealt face down and the dealer's cards are dealt four cards face down and one card face up. Each player views his hand and then decides whether to continue to play by making an additional bet or to fold or drop, in which case he loses his ante. The dealer then reveals his entire hand; if the dealer's hand does not have a poker value of at least Ace-King, then the dealer is not permitted to continue to play. In that case, the dealer pays even money on the remaining players' antes, and returns their bets to them. If the dealer's hand has a poker value of Ace-King or better, the dealer compares his hand to each player's hand, paying or collecting the bets as appropriate. The dealer also pays odds of more than even money on each winning player's hand of two pair or better according to a bonus payment schedule. This game can be played using the gaming table shown in FIG. 1. Each player makes a progressive jackpot wager by placing a gaming token in the coin acceptor **20** which makes that player eligible to participate in the progressive jackpot amount shown on the meter **70**. The winning hands and amounts for Caribbean Stud™ Poker are preferably as follows:

Hand	Amount
Royal Flush	100%
Straight Flush	10%
Four of a Kind	1%
Full House	50 tokens
Flush	25 tokens

Again the invention is not limited to these particular combinations of hands or payoff amounts; other hand combinations or payoff amounts can be utilized.

The invention can also be adapted to other casino or cardroom poker games such as Stud Poker, Draw Power or

Lo-Ball Poker. The gaming table 100 used to play each of these games is modified as shown in FIG. 2 by the addition of coin acceptors 120 and indicator signals 122 at each player's location 112. The electronics is the same as that shown in FIG. 1 and includes a main control board 140, an odometer-type counter 142, a progressive jackpot control box 160, a progressive jackpot meter 170 and a jackpot reset control 180. A reset switch 150 and a lockout switch 155 are located adjacent the dealer's location 114 next to the chip rack 116.

The progressive jackpot meter 170 is incrementally increased in the same manner as that described in connection with FIG. 1 by each player placing a gaming token in the coin acceptor 120.

The winning hands and payoff amounts are preselected as appropriate for the type of game being played. In the preferred embodiment, the winning hands and payoff amounts are as follows:

Hand	Amount
<u>I. Five Card Draw Poker</u>	
Royal Flush	100%
Straight Flush	10%
Four of a Kind	100 tokens
Full House	25 tokens
<u>II. Five Card Stud Poker</u>	
Royal Flush	100%
Straight Flush	10%
Four of a Kind	100 tokens
Full House	25 tokens
<u>III. Seven Card Stud Poker</u>	
Royal Flush	100%
Straight Flush	10%
Four of a Kind	100 tokens
Full House	25 tokens
<u>IV. Lo-Ball Poker</u>	
5-4-3-2-Ace	100%
6-4-3-2-Ace	5%
6-5-3-2-Ace	100 tokens
7-4-3-2-Ace	25 tokens

These winning hands and payoff amounts are merely preferred embodiments and the invention may be practiced using any appropriate combination of winning hands and payoff amounts.

As an alternative embodiment, progressive jackpot component of the game may be utilized as a consolation payoff for a player who otherwise loses during the play of the regular game. For example, assume the regular game being played is Five Card Stud. Players A and B are both eligible for the progressive jackpot amount because each has placed a gaming token in the coin acceptor prior to the beginning of the play of the hand. Player A holds a hand having Four of a Kind. Player B holds a Full House. Because Player A's hand is higher according to the customary poker hand ranking priority, Player A wins the pot wagered on the Five Card Stud game. As a consolation, however, Player B receives a payoff amount from the progressive jackpot for his Full House, e.g., 25 tokens. Player A does not receive a payoff from the progressive jackpot because he already has won the pot from the regular Five Card Stud game. Thus, under this alternative embodiment, a player only receives a payoff from the progressive jackpot if the player both has a hand of the preselected type and loses to a higher hand in the game being played.

Another modification would have the two players sharing in the progressive jackpot amount; the player with the preselected type of hand receiving a percentage of the progressive jackpot amount and the player with the higher poker hand receiving the rest of the progressive jackpot amount. With reference to the example above, Player B would receive 80% of the progressive jackpot amount for a Full House and Player A would receive 20% of the progressive jackpot amount for a Full House.

FIG. 3 shows in block diagram form the operation of the present invention. Each playing location has a coin acceptor 210 into which a player places a gaming token in order to be eligible for the progressive jackpot amount. When all players have had sufficient time to decide whether to participate in the progressive jackpot for that hand the dealer activates the lockout switch 220 which prevents late wagers. Each gaming token placed in a coin acceptor 210 energizes the progressive output control 230 which in turn activates three separate devices. An integrated circuit timer is energized which causes an indicator light 250 to be illuminated at the location on the coin acceptor in front of the player. This gives a visual indication to the dealer that that player is participating in the progressive jackpot during the play of that hand.

The signal from the progressive jackpot control 230 also activates an odometer-type counter 255 which increments by one unit for each gaming token wagered through the coin acceptor. This allows the gaming establishment to keep an accurate account of the number of wagers made on the progressive jackpot.

The third signal from the progressive jackpot control 230 goes directly to the progressive jackpot meter 270. The progressive jackpot meter 270 shows the total amount available to be won by a player who obtains one of the preselected winning hands. The amount of the progressive jackpot meter 270 automatically increases a predetermined amount for each gaming token placed in the coin acceptor. The progressive jackpot meter 270 is programmed to increase a specified percentage of the amount wagered in the coin acceptor 210. In the preferred embodiment, the progressive jackpot meter will be increased between about 93% to 97% of the amount wagered in the coin acceptor 210.

The dealer then deals the cards to each player and the hand is played 280. If a player has a preselected winning hand, the player is paid the amount corresponding to the type of winning hand that the player has. The jackpot reset control 290 is manually activated which results in the amount of payoff being automatically deducted from the amount displayed on the progressive jackpot meter 270.

After the winning players have been paid, the dealer activates the reset switch 295 which both turns off the integrated circuit timer 240 and turns off the indicator light 250 and the dealer deactivates the lockout switch 297 thereby activating the coin acceptor 210 for the next hand.

FIG. 4 in schematic form depicts the electronic circuitry to operate the apparatus of the present invention. The coin acceptor circuitry 300 is activated when a gaming token is dropped into the slot on the gaming table where the coin acceptor is mounted. The gaming token passes between an ultraviolet transmitter DS1 and an optic receiver Q1 (Model #MRD 300 transistor). This causes a pulse to be passed from the collector of Q1 to the base of receiver Q2. Q2 is a Model #2N3906 transistor and acts as an emitter follower and sends a pulse which is received by the integrated circuit 322,324 of the main control board 320. The integrated circuit 322,324 is a Model #LM-556 Timer. The pulse from Q2 is received at pin 325 of the lower portion 324 of the integrated

circuit and this pulse causes pin **326** of the lower portion **324** to go high and turn on diode **DS2** (a Model P367 diode). This diode **DS2** is the indicator light **22** shown in FIG. 1 and this indicator light **22** stays on until the play of the hand is finished.

The pulse from **Q2** also is received by pin **323** on the upper portion **322** of the integrated circuit and this pulse creates a pulse at pin **327** of the upper portion **322** which causes transistor **Q3** (a Model #T1P120 transistor) to turn on, then off for the duration of the pulse created at pin **327**. The turning on and off of transistor **Q3** causes the odometer-type counter **42** shown in FIG. 1 to increment one digit. The odometer-type counter **330** is a six-digit non-resetable electronic 12VDC counter, WICO Model #31-443400.

The pulse created at pin **327** of the upper portion **322** of the integrated circuit also goes to the opto isolator **340** (which is a Model #H11A16E Opto Isolator). The opto isolator **340** passes this pulse to the base of transistor **Q4** (a Model #2N3906 transistor) thereby turning on transistor **Q4** for the duration of the pulse. When transistor **Q4** is turned on, the pulse is passed to the progressive jackpot display meter **350** where the amount shown on the display meter **350** is increased by a predetermined percentage of the value of the gaming token placed in the coin acceptor **300**. The progressive jackpot display meter **350** can typically be a Game Technology Model having 3" LED characters on a 44" length single progressive display.

After all bets are made, the dealer manually presses a lockout switch **360** which will clamp the output of the transistor **Q2** at a low level which ensures that there can be no late wagers made through the coin acceptor **300**. Once the output of the transistor **Q2** is clamped at a low level, a gaming token placed in the coin acceptor **300** will not cause a pulse to flow through the rest of the circuitry.

The game is then played and once the game is completed, the dealer will manually press the reset switch **370** which creates a reset pulse that activates pin **320** which resets the lower portion **324** of the integrated circuit. This resetting causes pin **326** to go low which will extinguish diode **DS2** which turns off the indicator light **22** on the gaming table.

The dealer also manually presses the lockout switch **360** to open the circuit and remove the clamp on the emitter of transistor **Q2** which allows another hand to be played. The players commence the next hand by placing gaming tokens in the coin acceptor **300** and the process is repeated.

As will be apparent to those skilled in the art, various resistors and capacitors are provided to complete the circuitry. The specifications on the resistors and capacitors shown in FIG. 4 is as follows:

Registers	Capacitors
R1-68 Ohm	C1-.1 ufd/35 v
R2-3 Kohm	C2-.01 ufd/35 v
R3-1 Kohm	C3-.2 ufd/35 v
R4-200 Ohm	C4-.1 ufd/35 v
R5-4.7 Kohm	
R6-10 Kohm	
R7-1 Mohm	
R8-240 Ohm	
R9-1 Kohm	
R10-4.7 Kohm	
R11-240 Ohm	
R12-1 Kohm	

While the present invention has been particularly shown and described with reference to the preferred mode as illustrated in the drawing, it will be understood by one

skilled in the art that various changes in detail may be effected therein without departing from the spirit and scope of the invention as defined by the claims.

What is claimed is:

5 1. A method of including a jackpot component as an additional feature in a card game, said jackpot component including at least one progressive amount and at least one non-progressive amount, comprising the steps of:

10 (a) a player making at least one game wager to participate only in the card game;

(b) the player optionally making at least one jackpot wager to participate in the jackpot component, wherein no portion of said at least one jackpot wager contributes toward the play or winnings of said card game;

(c) playing said card game only after the player has made said game wager and decided whether to optionally make said jackpot wager;

(d) determining whether a player who has made said least one jackpot wager has won according to a predetermined set of rules; and

(e) paying to said winning player who has made said at least one jackpot wager at least a portion of said at least one progressive amount.

2. The method of claim 1, wherein said portion of said progressive amount is predetermined.

25 3. The method of claim 1, wherein said portion of said progressive amount is 100%.

30 4. The method of claim 1, further comprising the step of visibly displaying said progressive amount on a meter positioned in view of the player.

35 5. The method of claim 1, wherein any progressive amount that is not won on the first game carries over to the next game.

6. The method of claim 1, wherein said card game comprises a poker game.

35 7. The method of claim 6, wherein said card game comprises a casino poker game.

40 8. The method of claim 7, comprising the additional steps of providing at least one light associated with the player and indicating the making of said at least one jackpot wager by the player by illuminating the at least one light associated with the player making said at least one jackpot wager.

45 9. The method of claim 1, wherein said card game comprises a casino twenty-one game.

10. The method of claim 8, comprising the additional steps of providing at least one light associated with the player and indicating the making of said at least one jackpot wager by the player by illuminating the at least one light associated with the player making said at least one jackpot wager.

50 11. The method of claim 1, wherein said jackpot component includes at least two progressive amounts and at least two non-progressive amounts.

12. The method of claim 1, comprising the additional steps of providing at least one light associated with the player and indicating the making of said at least one jackpot wager by the player by illuminating the at least one light associated with the player making said at least one jackpot wager.

60 13. The method of claim 1, wherein said jackpot component includes at least two non-progressive amounts each having a value determined as a ratio of at least 100 times the amount of said at least one jackpot wager.

14. A method of including a prize component as an additional feature in a card game, said prize component including at least three different prizes, comprising the steps of:

- (a) a player making at least one game wager to participate only in the card game;
- (b) the player optionally making at least one prize wager to participate in the prize component, wherein no portion of said at least one prize wager contributes toward the play or winnings of said card game;
- (d) determining whether a player who has made said at least one prize wager has won according to a predetermined set of rules; and
- (e) paying to said winning player who has made said at least one prize wager at least one of said prizes.

15. The method of claim 14, wherein said card game comprises a poker game.

16. The method of claim 14, comprising the additional steps of providing at least one light associated with the player and indicating the making of said at least one prize wager by the player by illuminating the at least one light associated with the player making said at least one prize wager.

17. A method of including a jackpot component as an additional feature in a card game, said jackpot component including at least one progressive jackpot amount, comprising the steps of:

- (a) establishing at least one rule by a player may win said at least one progressive jackpot amount;
- (b) affording a player an opportunity to make at least one game wager to participate only in the card game;
- (c) affording the player an opportunity to make at least one jackpot wager to participate in the jackpot component, wherein no portion of said at least one jackpot wager contributes to the play or winnings of said card game, with steps (a)–(c) performed in any sequence;
- (d) after steps (a)–(c), providing a plurality of cards to each player who has made said at least one game wager;
- (e) after step (d), determining whether any player who has made said at least one jackpot wager has won according to said at least one rule;
- (f) after step (d), settling any said at least one game wager made by any players; and
- (g) after step (e), settling any said at least one jackpot wagers made by any players, with steps (f) and (g) performed in any sequence.

18. The method of claim 17, wherein said jackpot component includes at least one progressive amount and at least two non-progressive amounts, wherein said establishing step establishes at least one set of rules by which a player may win said at least one progressive amount and said at least two non-progressive amounts, and wherein said determining step determines whether any player has made said at least one jackpot wager has won according to said at least one set of rules.

19. The method of claim 18, wherein said card game comprises a poker game.

20. The method of claim 18, wherein said card game consists essentially of a poker game.

21. The method of claim 18, wherein said card game 60 consists essentially of a casino poker game.

22. The method of claim 18, wherein said card game comprises a twenty-one game.

23. The method of claim 18, wherein said card game 65 consists essentially of a twenty-one game.

24. The method of claim 18, wherein said card game consists essentially of a casino twenty-one game.

25. The method of claim 18, wherein each of said least two non-progressive amounts has a value determined as a ratio of at least 100 times the amount of said at least one jackpot wager.

5 26. The method of claim 17, wherein said card game comprises a poker game.

27. The method of claim 17, wherein said card game consists essentially of a poker game.

10 28. The method of claim 17, wherein said card game consists essentially of a casino poker game.

29. The method of claim 17, wherein said card game comprises a twenty-one game.

30. The method of claim 17, wherein said card game consists essentially of a twenty-one game.

15 31. The method of claim 17, wherein said card game consists essentially of a casino twenty-one game.

32. The method of claim 17, wherein said at least one rule includes a determination of whether the plurality of cards provided to the player in step (d) consists of a selected arrangement.

20 33. The method of claim 32, wherein said card game comprises a poker game.

34. The method of claim 32, wherein said card game consists essentially of a poker game.

35. The method of claim 32, wherein said card game 30 consists essentially of a casino poker game.

36. The method of claim 32, wherein said card game consists a twenty-one game.

37. The method of claim 32, wherein said card game 35 consists essentially of a twenty-one game.

38. The method of claim 32, wherein said card game consists essentially of a casino twenty-one game.

39. The method of claim 32, comprising the additional steps prior to step (d) of providing at least one light 35 associated with each player position and indicating the making of said at least one jackpot wager by illuminating the at least one light associated with the location of the player making said at least one jackpot wager.

40. The method of claim 17, comprising the additional steps prior to step (d) of providing at least one light associated with the player and indicating the making of said at least one jackpot wager by illuminating the at least one light associated with the player making said at least one jackpot wager.

41. A method of affording each player who participates in a card game an opportunity to win one of a plurality of prizes in addition to any amounts won in connection with the play of said card game, wherein each of said additional prizes corresponds to one of a plurality of winning arrangements of cards selected before the players receive cards, comprising the steps of:

(a) affording a player an opportunity to make at least one game wager to participate only in the card game;

(b) affording the player an opportunity to make at least one prize wager in order to be eligible to win at least one of said additional prizes, wherein said at least one prize wager does not contribute to the play or winnings of said card game;

(c) providing at least one light associated with each player position, with steps (a)–(c) performed in any sequence;

(d) after step (b), indicating the making of said at least one prize wager by the player by illuminating the at least one light associated with the position of the player making said at least one prize wager;

(e) after steps (a)–(d), providing cards to each player who has made said at least one game wager; and

11

(f) awarding one of said prizes to a player only if the player has been provided cards comprising at least one of said winning arrangements of cards and only if the player opted to make said at least one prize wager.

42. The method of claim 41, wherein said card game comprises a poker game. 5

43. The method of claim 41, wherein said card game consists essentially of a casino table poker game.

44. The method of claim 43, wherein said winning arrangements include a royal flush, a straight flush, and four of a kind. 10

45. The method of claim 41, wherein said card game comprises twenty-one.

46. The method of claim 41, wherein said card game consists essentially of twenty-one.

47. The method of claim 41, wherein said winning arrangements include four cards of the same rank and suit.

48. The method of claim 41, wherein the player is awarded a prize in step (f) only if the player has been provided cards consisting of at least one of said winning arrangements of cards. 20

49. A method of affording each player who participates in a poker card game an opportunity to win one of a plurality of prizes in addition to any amounts won in connection with the play of said poker card game, wherein each of said additional prizes corresponds to one of a plurality of winning arrangements of at least three cards selected before the players receive cards, and wherein the corresponding additional prize for a higher ranked poker hand is of greater value than the corresponding additional prize for a lower ranked poker hand, comprising the steps of:

- (a) affording a player an opportunity to make at least one game wager to participate only in the poker card game;
- (b) affording the player an opportunity to optionally make at least one prize wager in order to be eligible to win at least one of said additional prizes, wherein said at least one prize wager does not contribute to the play or winnings of said poker card game, with steps (b) and (c) in any sequence;
- (c) electronically recognizing the making of said at least one prize wager;
- (d) after steps (a)–(c), providing cards to each player who has made said at least one game wager until the player achieves a hand consisting of at least three cards; and
- (e) awarding one of said prizes to a player only if the player's hand comprises at least one of said winning arrangements of at least three cards and only if the player opted to make said at least one prize wager.

50. The method of claim 49, wherein said poker game consists essentially of stud poker.

51. The method of claim 49, wherein said winning arrangements of at least three cards include a royal flush, a straight flush, four of a kind, a full house, a flush, and a straight.

52. A method of affording a player who participates in a card game an opportunity to win one of at least three different prizes in addition to any amounts won in connection with the play of said game, wherein each of said additional prizes corresponds to one of a plurality of winning arrangements of cards selected before the player receives cards, comprising the steps of:

- (a) establishing at least one set of rules by which the player may win at least one of said additional prizes;
- (b) affording a player an opportunity to make at least one game wager to participate only in the card game;
- (c) affording the player an opportunity to make at least one prize wager in order to be eligible to win at least

12

one of said additional prizes, wherein no portion of said at least one prize wager contributes to the play or winnings of said card game, with the steps (a)–(c) performed in any sequence;

(d) after steps (a)–(c), providing a plurality of cards to the player if the player has made said at least one game wager;

(e) after step (d), determining whether the player has made said at least one prize wager and has won according to said at least one set of rules;

(f) after step (d), settling any said at least one game wagers made by the player; and

(g) after step (e), settling any said at least one prize wagers made by the player, with steps (f) and (g) performed in any sequence. 15

53. The method of claim 52, wherein said additional prizes include at least one progressive amount and at least two non-progressive amounts, and wherein said establishing step establishes at least one set of rules by which a player may win said at least one progressive amount and said at least two non-progressive amounts.

54. The method of claim 53, wherein said card game comprises a poker game.

55. The method of claim 53, wherein said card game consists essentially of a poker game. 25

56. The method of claim 53, wherein said card game consists essentially of a casino stud poker game.

57. The method of claim 53, wherein said card game comprises a twenty-one game.

58. The method of claim 53, wherein said card game consists essentially of a twenty-one game.

59. The method of claim 53, wherein said card game consists essentially of a casino twenty-one game.

60. The method of claim 53, comprising the additional steps prior to step (d) of providing at least one light associated with the player and indicating the making of said at least one prize wager by the player by illuminating the at least one light associated with the player making said at least one prize wager. 35

61. The method of claim 53, wherein each of said at least two non-progressive amounts has a value determined as a ratio of at least 100 times the amount of said at least one prize wager.

62. The method of claim 52, wherein said card game comprises a poker game. 40

63. The method of claim 52, wherein said card game consists essentially of a poker game.

64. The method of claim 52, wherein said card game consists essentially of a casino stud poker game.

65. The method of claim 52, wherein said card game comprises a twenty-one game.

66. The method of claim 52, wherein said card game consists essentially of a twenty-one game.

67. The method of claim 52, wherein said card game consists essentially of a casino twenty-one game. 55

68. The method of claim 52, comprising the additional steps prior to step (d) of providing at least one light associated with the player and indicating the making of said at least one prize wager by the player by illuminating the at least one light associated with the player making said at least one prize wager.

69. The method of including a jackpot component as an additional feature in a casino card game, said jackpot component including at least one progressive jackpot amount, comprising the steps of:

- (a) establishing at least one rule by which a player may win said at least one progressive jackpot amount;

- (b) affording a player an opportunity to make at least one game wager to participate only in the casino card game;
- (c) affording the player an opportunity to make at least one jackpot wager in order to be eligible to win said at least one progressive jackpot amount, wherein no portion of said at least one jackpot wager contributes to the play or winnings of said casino card game, with steps (a)–(c) performed in any sequence;
- (d) after steps (a)–(c), providing a plurality of cards to the player if the player has made said at least one game wager;
- (e) after step (d), determining whether the player has made said at least one jackpot wager and has won according to said at least one rule;
- (f) after step (d), settling any said at least one game wagers made by the player; and
- (g) after step (e), settling any said at least one jackpot wagers made by the player, with steps (f) and (g) performed in any sequence.

70. The method of claim 69, wherein said jackpot component includes at least one progressive amount and at least two non-progressive amounts, wherein said establishing step establishes at least one set of rules by which a player may win said at least one progressive amount and said at least two non-progressive amounts, and wherein said determining step determines whether any player who has made said at least one jackpot wager has won according to said at least one set of rules.

71. The method of claim 70, comprising the additional steps prior to step (d) of providing at least one light associated with the player and indicating the making of said at least one jackpot wager by the player by illuminating the at least one light associated with the player.

72. The method of claim 70, wherein each of said at least two non-progressive amounts has a value determined as a ratio of at least 100 times the amount of said at least one jackpot wager.

73. The method of claim 69, wherein said casino card game comprises a poker game.

74. The method of claim 69, wherein said casino card game consists essentially of a poker game.

75. The method of claim 69, wherein said casino card game comprises a twenty-one game.

76. The method of claim 69, wherein said casino card game consists essentially of a twenty-one game.

77. The method of claim 69, comprising the additional steps prior to step (d) of providing at least one light associated with the player and indicating the making of said at least one jackpot wager by the player by illuminating the at least one light associated with the player.

78. The method of claim 69, comprising the additional step after step (c) of increasing said at least one progressive jackpot amount in response to the making of said at least one jackpot wager by the player.

79. The method of claim 78, comprising the additional step prior to step (d) of displaying said at least one progressive jackpot amount on at least one sign viewable by the player.

80. The method of claim 79, wherein said casino card game consists essentially of a twenty-one game.

81. The method of claim 80, wherein said at least one rule includes whether the cards provided to the player in step (d) consist of a predetermined arrangement of cards.

82. The method of claim 78, wherein said at least one rule includes whether the cards provided to the player in step (d) consist of a predetermined arrangement of cards.

83. The method of claim 69, comprising the additional step prior to step (d) of displaying said at least one progressive jackpot amount on at least one sign viewable by the player.

84. The method of claim 69, wherein said at least one rule includes whether the cards provided to the player in step (d) consist of a predetermined arrangement of cards.

85. A method of including a jackpot component as an additional feature in a twenty-one card game, said jackpot component including at least one progressive jackpot amount, comprising the steps of:

- (a) establishing at least one rule by which a player may win at least a portion of said progressive jackpot amount if the cards dealt to the player during the game consist of a selected arrangement of cards;
- (b) affording a player an opportunity to make at least one game wager to participate only in the game;
- (c) affording the player an opportunity to make at least one progressive jackpot wager in order to be eligible to win said at least a portion of said jackpot amount, wherein no portion of said at least one jackpot wager contributes to the play or winnings of said game, with steps (a)–(c) performed in any order;
- (d) after step (c), increasing said at least one progressive jackpot amount in response to making of said at least one jackpot wager;
- (e) after step (d) and before step (f), displaying said at least one progressive jackpot amount on at least one sign viewable by the player;
- (f) after steps (a)–(c), dealing a plurality of cards to the player, if the player has made said at least one game wager; and
- (g) after step (f), determining if the player has made said at least one jackpot wager and has been dealt cards consisting of said selected arrangement of cards and, if so, awarding to the player said at least a portion of said progressive jackpot amount.

86. The method of claim 85, wherein said at least a portion of said progressive jackpot amount is 100% of said progressive jackpot amount.

87. A method of affording a player who participates in a card game an opportunity to win one of at least three different prize amounts in addition to amounts won in connection with the play of said card game, wherein said player may participate in said card game by making at least one game wager and may participate in said opportunity by making at least one prize wager, each of said at least three different, additional prize amounts being a non-progressive amount equal to an associated, different multiple value of said at least one prize wager, and at least one of said at least three different, additional prize amounts being a non-progressive amount determined as a ratio of at least 100 times the value of said at least one prize wager, each of said at least three different, additional prize amounts corresponding to an associated one of at least three different winning conditions, said at least three different, additional prize amounts and said at least three different winning conditions selected before said player receives cards to play said card game, said method comprising:

- (a) allowing said player to make at least one game wager to participate only in said card game;
- (b) affording said player an opportunity to optionally make at least one prize wager in order to be eligible to win at least one of said different, additional prize amounts wherein said at least one prize wager does not contribute to the play or winnings of said card game;

- (c) after steps (a) and (b), which may be performed in any sequence, providing cards to said player if said player has made said at least one game wager; and
- (d) after step (c), awarding one of said different, additional prize amounts to said player only if said player has achieved one of said at least three different winning conditions and only if said player opted to make said at least one prize wager.

88. The method of claim 87 wherein each of said at least three different winning conditions is whether the cards provided to said player comprise a particular arrangement.

89. The method of claim 88 wherein each of said at least three different winning conditions is whether the cards provided to said player consist of a particular arrangement.

90. The method of claim 89, wherein at least five cards are provided to said player in step (c).

91. The method of claim 88 wherein at least five cards are provided to said player in step (c).

92. The method of claim 87, wherein at least five cards are provided to said player in step (c).

93. The method of claim 87 wherein said card game consists essentially of a twenty-one game.

94. The method of claim 87 wherein said card game consists essentially of a casino twenty-one game.

95. The method of claim 94 wherein at least two of said at least three different, additional prize amounts are each non-progressive amounts determined as a ratio of at least 25 times the value of said at least one prize wager.

96. The method of claim 87 wherein at least two of said at least three different, additional prize amounts are each non-progressive amounts determined as a ratio of at least 25 times the value of said at least one prize wager.

97. The method of claim 87 wherein said card game consists essentially of a casino poker game.

98. A method of affording a player who participates in a card game an opportunity to win one of at least three different prize amounts in addition to amounts won in connection with the play of said card game, wherein said player may participate in said card game by making at least one game wager and may participate in said opportunity by making at least one prize wager, each of said at least three different, additional prize amounts being a non-progressive amount equal to an associated, different multiple value of said at least one prize wager, and at least one of said at least three different, additional prize amounts being a non-progressive amount determined as a ratio of at least 100 times the value of said at least one prize wager, each of said at least three different, additional prize amounts correspond-

ing to an associated one of at least three different winning conditions, said at least three different, additional prize amounts and said at least three different winning conditions selected before said player receives cards to play said card game, said method comprising the steps of:

- (a) allowing said player to make at least one game wager to participate only in said card game;
- (b) affording said player an opportunity to optionally make at least one prize wager in order to be eligible to win at least one of said different, additional prize amounts wherein said at least one prize wager does not contribute to the play or winnings of said card game;
- (c) after steps (a) and (b), which may be performed in any sequence, providing cards to said player if said player has made said at least one game wager; and
- (d) after step (c), awarding one of said different, additional prize amounts to said player only if said player has achieved one of said at least three different winning conditions and only if said player opted to make said at least one prize wager.

99. The method of claim 98 wherein each of said at least three different winning conditions is whether the cards provided to said player comprise a particular arrangement.

100. The method of claim 99 wherein each of said at least three different winning conditions is whether the cards provided to said player consist of a particular arrangement.

101. The method of claim 100, wherein at least five cards are provided to said player in step (c).

102. The method of claim 99 wherein at least five cards are provided to said player in step (c).

103. The method of claim 98, wherein at least five cards are provided to said player in step (c).

104. The method of claim 98 wherein said card game consists essentially of a twenty-one game.

105. The method of claim 98 wherein said card game consists essentially of a casino twenty-one game.

106. The method of claim 105 wherein at least two of said at least three different, additional prize amounts are each non-progressive amounts determined as a ratio of at least 25 times the value of said at least one prize wager.

107. The method of claim 98 wherein at least two of said at least three different, additional prize amounts are each non-progressive amounts determined as a ratio of at least 25 times the value of said at least one prize wager.

108. The method of claim 98 wherein said card game consists essentially of a casino poker game.
